4 Claims. (Cl. 313—65)

1

The present invention relates to cathode ray tubes and more particularly to cathode ray image converter tubes and to a method for manufacturing the same.

Cathode ray image converter tubes serve as optical instruments for converting light images of one wavelength into light images of another, usually visible, wavelength and for amplifying images of low brightness. These tubes usually comprise a photo-electrically active layer responsive to the impinging radiation, an electron lens system for focussing the electrons emitted by the photo-electric layer into an electron image and a fluorescent projection screen for converting the electron image into an image of the desired wavelength, usually visible. When such tubes comprise a cathode sensitive to infra-red radiation, they may be used for observing objects in the dark or mist.

To indicate the center of the field of view of the image converter tube, it has been proposed to provide cross-wires on the fluorescent screen. Other marks such as graduations or small divisions have been similarly provided. However, this arrangement has not proven satisfactory due to displacement of the electron image relatively to the fixed mark under the action of undesired electric or magnetic fields. Such a displacement may, for example, be caused by the terrestrial magnetic field.

To obviate this disadvantage, it has been proposed to project an image of cross-wires onto the photo-electrically active layer by means of an additional lens in the optical system arranged in front of the tube. Since a displacement of the fluorescent image involves a shift of the image of the cross-wires, the position of the wire cross thus remains unchanged with respect to the field observed. This arrangement has the disadvantage of requiring an additional lens thereby making the optical system more complicated and costly.

In accordance with the invention, the above disadvantages are obviated by providing at the carrier of the photoelectrically active layer an object which projects itself electronoptically as a mark onto the projection screen.

As a rule the carrier for the photoelectric layer is constituted by the wall of the discharge tube. In this event, a figure projecting itself as a mark may be provided at the exterior of this wall. This is an extremely simple method, but has the disadvantage that the plane of the figure does not coincide with the place of the photoelectric layer so that a sharply focussed image of the

figure is not formed on the fluorescent screen. Furthermore, the thickness of the tube wall is usually too great to obtain a sufficiently sharp shadow of the figure.

Therefore, in accordance with the preferred embodiment of the invention, the figure to be projected is located underneath the photo-electrically sensitive layer on the carrier thereby intercepting the impinging light rays. The figure to be projected as a mark may alternatively be produced in a different manner, for example by the local removal of the photo-electric material in accordance with the desired pattern or by providing a material preventing activation of the photo-electric material at a given area thereof.

The invention will be described in greater detail with reference to the appended drawing forming part of the specification and in which:

Fig. 1 is a section through the axis of a lumino-scope in accordance with the invention, and

Fig. 2 being a cross-section on the plane II—II.

The tube comprises an exhausted glass vessel having a cylindrical part 1, a spherical part or cathode carrier 2 and a bottom part 3. The part 2 is internally coated with a thin but opaque aluminum layer 4. A supply conductor 5 passed through the wall of the tube in a vacuum-tight manner, is connected to this layer. A window 6 has been left free at the centre of the opaque layer. A second very thin transparent layer extends over the layer 4 and the window 6, this second layer having been produced by precipitating silver or a different suitable metal and sensitised under the action of oxygen and caesium vapour in a known manner such as to act as a photo-electric cathode.

The thickness of the layers 4 and 7 is exaggerated in the drawing. The opaque layer actually has, for example, a thickness of 0.1 micron, the layer 7 usually having a thickness only of several atoms.

The bottom part 3 comprises a flat plate 8 carrying the fluorescent screen 9. Furthermore, it carries a metal hood 10 constituting the anode or electron focussing member of the tube. The spherical cap 11 of the anode and the concave cathode surface jointly constitute an electron-optical system by which the cathode-rays passing through an aperture 12 provided in the anode cap are focussed in such manner as to produce an image of the window 6 on the screen 9. A supply conductor 13 passing through the bottom part 3 in a vacuum-tight manner is secured to the anode.

The window 6 is formed during the application

of the layer 4 and this is effected by means of a mask arranged on the inner wall of the spherical part 2, which mask is removed prior to applying the photo-electrically active layer. This mask has an aperture consisting of four slits jointly forming a small cross with the point of intersection in the axis of the tube, thus creating on the wall of the tube a figure 14 corresponding to the aperture of the mask on applying the layer 4. This figure intercepts extraneous light rays and when projecting an image onto the sensitive layer 7 by means of a suitable optical system (not shown). The same figure is observed through the transparent plate 8 on the fluorescent screen 9 as a cruciform mark.

The figure 14 and the layer 4 are preferably formed by vacuum vaporization of a suitable metal, for example, by vaporizing aluminum, silver or the like from a suitable chamber electrically heated by a tungsten filament. Subsequently, the mask is removed and the bulb is closed by a bottom comprising the anode 11 and a fluorescent screen 9. After the tube has again been exhausted, another layer of metal, for example, of silver or antimony is precipitated onto the cathode carrier 2, but now to such a thinness as to be transparent. It is customary to form this deposit by heating a piece of metal arranged in the bulb, for example by means of a high-frequency magnetic field.

The so deposited wall-coating is made photo-electrically active by introducing oxygen and subsequently caesium vapour into the tube. It now emits electrons when extraneous light falls on the cathode, but only where the latter is free from the opaque layer, that is the area of the removed mask, except for the figure recessed therein, where extraneous light rays cannot penetrate to the photo-electrically active layer, so that the latter is made inactive.

What we claim is:

1. A cathode ray image converting device comprising a carrier member, a photoelectric layer mounted on said carrier member and having an active area with a given boundary, said carrier member having within the boundary of said area a portion defining a non-photoelectrically active figure of given configuration on said photoelectric layer, an electron-responsive screen, and an

electron focussing member interposed between said layer and said screen.

2. A cathode ray image converting device comprising a carrier member, a photoelectric layer mounted on one side of said carrier member and having an active area with a given boundary, said carrier member having on the said one side and within said area a portion defining a non-photoelectrically active figure of given configuration on said photoelectric layer, an electron-responsive screen, and an electron focussing member interposed between said layer and said screen.

3. A cathode ray image converting device comprising a carrier member, a photoelectric layer mounted on one side of said carrier member and having an active area with a given boundary, a layer of opaque material on said carrier member and surrounding said active area, said carrier member having on the said one side and within said area a portion of opaque material defining a non-photoelectrically active figure of given configuration on said photo-electric layer, an electron-responsive screen, and an electron focussing member interposed between said layer and said screen.

4. A cathode ray image converting device comprising a transparent envelope portion, a photoelectric layer mounted on one side of said envelope portion and having an active area with a given boundary, an opaque layer of aluminum on said envelope portion and surrounding said active area, said envelope portion having on the inside thereof and within said area an aluminum deposit defining a non-photoelectrically active figure of given configuration on said photo-electric layer, a fluorescent screen, and an electron focussing member interposed between said layer and said screen.
